ELECTRICAL CONNECTOR

Carroll A. Badeau, Westfield, N. J., assignor to
 The Thomas & Betts Co., Elizabeth, N. J., a
 corporation of New Jersey

Application September 17, 1947, Serial No. 774,565

4 Claims. (Cl. 24—125)

1

This invention relates to a new electrical connector, sometimes referred to as a parallel connector, adapted for splicing and tapping conductor wires and cables for current transmission.

A purpose of the invention is to provide a new electrical connector which is so designed and constructed as to increase the positiveness and durability of its pressure connection when used to join electrical conductors in line for splicing together two wires as well as when tap connecting them in an angular or cross relation for leading a branch wire to lighting and other electrical equipment.

A further purpose is to produce a simple two-piece connector, as an improvement upon the old U-body type, which loops around a conductor or conductors under screw pressure and which embodies means to eliminate all shearing tendency of the clamping screw in order to prevent damage to conductors when anchored under clamping pressure within the body of the connector and also to eliminate fatigue in a wiring installation by which to maintain the initial maximum pressure on a wiring connection.

The accompanying drawings illustrate the simplicity of construction of this electrical connector, as compared to known U-body types, and demonstrate its utility in two principal applications of electrical wiring installations, as follows:

The first three views of the drawings show the connector without the conductors, while the last four views show two applications of the connector to conductors in the make-up of wiring installations.

Fig. 1 is a side view with diagram lines applied thereto for reference in the description to follow.

Fig. 2 is an end view of the electrical connector.

Fig. 3 is a transverse section taken on the line 3—3 through the body of the connector looking into the end of its clamping screw.

Figs. 4 and 5 are comparison views showing the connector joining or splicing two conductors in line or in parallel.

Fig. 4 shows a longitudinal section before applying clamping pressure; and Fig. 5 is a similar view after tightening the clamping screw under pressure.

Fig. 6 is a side view, and Fig. 7 is a bottom view of the connector with two conductors disposed at an angle, as for example, lapped cross-wise of each other and under clamping pressure in the connector body.

Referring further to the drawings for a description of an example of an embodiment of the

2

invention, it will be seen that a connector of modified U-body type is here characterized and improved by inwardly converging arms having angular seats which engage the conductors and secure them together (either in alignment or in cross relation) in a new manner with resulting advantages in wiring installations (splicing and tapping) calling for this type of connector.

The connector body may be die-formed from sheet copper and includes a head portion 10 with two shoulders 11 and two integral arm portions 12 made of flat stock. The head 10 is hole extruded and screw-tapped to receive an operating or clamping screw 13 with its inner end extending inward and midway of the arms 12. The screw 13 is adapted to be tightened into clamping pressure by screwing it inward against the near or uppermost conductor of the two wires W as shown in the drawings which illustrate insulated wires of the solid type. The connector is also well adapted for use on wires and cables of the stranded type.

Of importance is the fact that the two arms 12 converge inward from their shoulders 11 and toward each other in an angular relation which disposes their outer free ends rather close together and in a spaced relation much less than that of said shoulders. In fact, the outer free ends of the two arms 12 are here shown as being spaced a distance less than the diameter of the clamping screw 12. Thus the two arms carried on the head 10 are not parallel (as in known types of connectors) but converge toward the axis of the screw. This is an important improvement in structure over the art in respect to prior U-shaped connectors, as further study of my invention will reveal.

Next, it is pointed out that each arm 12 is provided with an elongated aperture which defines two spaced arcuate wire-receiving seats having two inner edges 14 disposed comparatively close to the axis of the screw 13. The wire apertures 14 have a width adapted to the particular size of the wire W for which the connector is manufactured, that is, the width of the wire-opening seats 14 is slightly greater than the diameter of the bare or de-insulated portion of the wire. The length of the two apertures 14 extends parallel with the axis of the screw 13 and is slightly greater than the total diameter of the two wires W introduced into the connector. Also, it is seen that the two apertures 14 are axially aligned perpendicular to the axis of the screw 13.

A flange 15 is extruded outwardly from each

arm 12 and substantially rims each elongated aperture 14. The flanges are integral with the arms and are of maximum width at the outer free ends thereof but feather-edge into the surface of the arms toward the shoulders 11. Thus the flanges 15 have a tapering formation, being narrow as they approach the head 10 and wide at the free ends of the arms where the outer edges of said flanges are pointed to at 16. The two arm flanges 15, therefore, provide two large-area wire-contact seats 14, 16 at the outer free ends of the arms 12. These large-area seats insure an effective electrical contact and mechanical grip by the connector on the lower or outermost wire W, while the screw 13 establishes a good grip on the innermost wire W.

The illustration in Fig. 1 aids in explaining the invention. Parallel reference lines P are tangent to the outer margins of the shoulders 11 and are extended beyond the length of the converged arms 12 in order to demonstrate that the shoulder portions 11 are the widest part of the connector. In other words, the two wire-seat edges 16 are seen to be not wider apart than the two shoulders 11; in fact they are, preferably, well within the reference lines P and hence are spaced apart a distance less than that of the shoulders 11.

Now it is seen that the outer linear edges of the two flanges 15 may be substantially parallel if desired, while the arms 12 converge non-parallel toward each other. It is also observed that the thin or narrow portions of the flanges 15 do not necessarily follow around the edge contours of the wire apertures adjacent the head 10. However, the wide flange portions 15 do rim and follow around the edge contours of the arcuate aperture seats 14, 16 at the free ends of the two arms 12 to provide large-area bearing-contact seats for the outermost wire W placed therein.

Another feature of the invention resides in the angular relation of the two spaced arcuate wire seats 14, 16 to each other and to the axis of the wire W placed therein. It is seen that the two closely spaced inner edges 14 are located further from the axis of the wire W than the outer edges 16 and that such arrangement tilts the large-area seats 14, 16 at an angle to the wire axis. This novel feature causes the wire W initially to rest only upon the two outer edges 16 (Fig. 4) before the screw 13 is tightened for producing pressure engagement first at the biting edges 16 and then along the entire area of the wire seats 14, 16 (Fig. 5).

The foregoing novel features of construction eliminate the tendency of the screw 13—when tightened under maximum pressure for compressing the wires W in the connector—to bend, shear or break the wire strands and also prevent the arms 12 from spreading. In old connectors of the U-body type, the arms thereof are parallel and do not have a spacing at their outer free ends which is less than the screw diameter.

Consequently, in the old type connector, the great pressure of the clamping screw not only may bend and apply a shearing tendency against the outermost wire W in its seat but also may cause the old type parallel arms to spread. In other words, the inner edges of the old type wire seats squeeze and cut into the electrical conductor, thus damaging it, and in addition to the latter fault the old type parallel arms sometimes undergo a creeping-apart action which loosens the grip of the connector on its wires.

The use and operation of my new modified U-

body type of screw-pressure connector herein, with its new form of angular wire seats 14, 16 in pairs, possesses an advantage in the relation of the diameter of the screw 13 to the spacing of the outer free ends of the converging body arms 12 which loop around and embrace one or both conductor wires W. This new relation to the distance bridged by the wire or wires W, across the short open space between the two angular wire-receiving seats 14, 16 formed in the free ends of the arms, provides new results, as will be appreciated by further study of my new connector. As previously recited, the space or distance between the outer free ends of the arm pair 12 is not greater than—and preferably is less than—the diameter of the body of the screw 13.

Accordingly, the two spaced inner edges 14 of the wire seats at the free ends of the arms 12 are in alignment with the body of the screw 13—20 and not in alignment with the circumference thereof as in old connectors—so that the clamping pressure exerted by the screw is not applied critically at the edges 14 of the wire seats but inwardly thereof (in a new manner) on and along 25 and also within the area 14, 16 of said seats. This new structural feature prevents outward distortion of the shortened span of the wire or wires W which reach across the minimum open space from one arm 12 to the other arm 12 and, consequently, prevents the two arm seats from cutting 30 into the electrical conductor under the pressure of the clamping screw 13. Such feature also stays the two arms 12 from creeping apart under the clamping pressure of the screw.

When the first wire W is introduced through the apertured arms 12 it rests initially upon the two sharp arcuate edges 16 of the wire-receiving seats (Fig. 4). As clamping pressure is applied by the screw 13, the two seat edges 16 begin to bite through the oxide on the wire and gain a virgin-metal contact to produce an unusually effective electrical connection. The two seat edges 16 establish a bite on the bare wires which 40 permanently wedges the two arms 12 against spreading. As pressure of the screw 13 increases 45 (Fig. 5), the two inner edges 14 are drawn toward the wire W until surface-area engagement is established between the wire and the entire portion of the arcuate seats 14, 16.

Thus in mode of action, my new connector, firstly, bites into the wire W at the two points 16 (Fig. 4) for making positive electrical connection and, secondly, draws and wraps against the wire at the two points or edges 14 (Fig. 5) for 50 positive mechanical connection. It is believed that my new fitting herein is the first of its type in this particular class of connectors to achieve this dual-function connection with a single 55 clamping screw acting in conjunction with a simple looped-type body and leading to the new results herein recited.

The foregoing new mode of pressure connection—in its freedom from distortion of the wires W and shearing tendency thereagainst—also results in greater positiveness and duration, hence permanency of pressure connection. In other words, since distortion of the wires W does not occur, there is no tendency for my new connector to loosen gradually due to compression fatigue of the wires after a workman has tightened the screw 13 and left the job. In previous types of 60 U-body parallel arm connectors, the pressure of the screw in its old position eventually fatigues the conductors, and the latter gradually recede 65

70

from the tightened screw, with the result that prior type connectors do not maintain their initial maximum pressure on the conductors over a long period of time.

Now it is understood more clearly that the converging arms 12, which loop around and embrace the wire or wires W and progressively grip at the four spaced edges 14 and 16, do not have a tendency to spread apart under clamping pressure by a gradual creeping action along the bottom or outermost conductor W. In prior connectors having old-type parallel arms, the latter sometimes undergo a gradual creeping action away from the axis of the screw. Such old mode of operation leads eventually to loss of pressure by the connector on its wiring installation.

My new connector, with its converging arms 12, has its two spaced wire-receiving seat inner edges 14 in line with the body of the screw 13, and maximum clamping pressure is constant and permanent in its applied force axially of the screw and perpendicularly to the wires W. Hence, pressure of the connector does not exert a spreading force on its arms, and no loosening tendency develops from that source after a workman has installed the connector under final screw pressure. The initial clamping pressure remains constant and the installed connector is permanent and positive.

Accordingly, the converging arms 12, aided by the angular seat 14, 16 pair, constitute simple features in a new combination which provide against fatigue distortion of the conductors W, as well as providing against fatigue spreading by creeping tendency of the arms 11. Both of these conditions pose problems which are inherent in prior art connectors of the old parallel looped-arm U-body type, and either condition operates singly or together to work a gradual loosening-up of the old connectors after they have remained in service for a period sufficiently long to fatigue the conductors and/or fatigue the connector itself. My new connector is so designed and constructed as to overcome both of these faults, as will be apparent from the description herein and also as demonstrated by test and use of this connector.

The disclosure herein explains the principles of the invention and the best mode contemplated in applying such principles, so as to distinguish the invention from others; and there is particularly pointed out and distinctly claimed the part, improvement or combination, which constitutes the invention or discovery, as understood by a comparison thereof with the prior art.

This invention is presented to fill the need for a new and useful electrical connector. Since various modifications in construction, mode of operation, use and method, may and often do occur to others, after acquaintance with a particular invention, it is to be understood that this dis-

closure is exemplary of the principles and of equivalent constructions without being limited to the present showing of the invention.

What is claimed is:

5. An electrical connector comprising a body including a head integrally formed with two spaced arms, each arm being provided at its outer free end with an aperture, the two apertures being axially aligned and thereby forming two spaced seats which are adapted to receive and support electrical conductors disposed one upon and in engagement with the other, a clamping screw operatively mounted in the head and being adapted to apply pressure against and perpendicular to the conductors midway of the two axially-aligned spaced seats, and the outer free ends of the arms converging toward the longitudinal axis of the screw, with the two seats spaced apart a distance less than the diameter of the clamping screw.
10. An electrical connector as described in claim 1, and wherein the arms and head join on each side of the clamping screw to form spaced shoulders, and also including a flange formed along the edge of each aperture in each arm thus enlarging the areas of the seats supporting the electrical conductor, such connector being characterized by the fact that the outer edges of the flanges are spaced apart a distance less than the distance between the spaced shoulders.
15. An electrical connector as described in claim 1, each of the two spaced seats of which is disposed at an angle to the axis of the two aligned apertures, thereby providing a contact edge on each seat which initially engages the conductor, and the operation of the clamping screw of which first acts to bite the contact edges into the conductor and thereafter to draw the angular seats into final parallel pressure engagement with said conductor.
20. An electrical connector as described in claim 3, but further characterized in that the outer contact edge of each seat is closer to the axis of the two aligned apertures than the inner contact edge of each seat, whereby the initial biting engagement of said two outer contact edges act to increase the resistance against spreading of the seats away from each other.
25. An electrical connector as described in claim 3, but further characterized in that the outer contact edge of each seat is closer to the axis of the two aligned apertures than the inner contact edge of each seat, whereby the initial biting engagement of said two outer contact edges act to increase the resistance against spreading of the seats away from each other.
30. An electrical connector as described in claim 1, each of the two spaced seats of which is disposed at an angle to the axis of the two aligned apertures, thereby providing a contact edge on each seat which initially engages the conductor, and the operation of the clamping screw of which first acts to bite the contact edges into the conductor and thereafter to draw the angular seats into final parallel pressure engagement with said conductor.
35. An electrical connector as described in claim 1, each of the two spaced seats of which is disposed at an angle to the axis of the two aligned apertures, thereby providing a contact edge on each seat which initially engages the conductor, and the operation of the clamping screw of which first acts to bite the contact edges into the conductor and thereafter to draw the angular seats into final parallel pressure engagement with said conductor.
40. An electrical connector as described in claim 3, but further characterized in that the outer contact edge of each seat is closer to the axis of the two aligned apertures than the inner contact edge of each seat, whereby the initial biting engagement of said two outer contact edges act to increase the resistance against spreading of the seats away from each other.
45. An electrical connector as described in claim 3, but further characterized in that the outer contact edge of each seat is closer to the axis of the two aligned apertures than the inner contact edge of each seat, whereby the initial biting engagement of said two outer contact edges act to increase the resistance against spreading of the seats away from each other.
